US0D1051962S

(12) **United States Design Patent** (10) **Patent No.:** **US D1,051,962 S**
(45) **Date of Patent:** **** Nov. 19, 2024**

(54) **WELDING MACHINE**

(71) Applicant: **ZHEJIANG LIN LONG WELDING EQUIPMENT CO., LTD.**, Taizhou (CN)

(72) Inventors: **Yang Lin**, Taizhou (CN); **Wei Lin**, Taizhou (CN)

(73) Assignee: **ZHEJIANG LIN LONG WELDING EQUIPMENT CO., LTD.**, Taizhou (CN)

(**) Term: **15 Years**

(21) Appl. No.: **29/849,311**

(22) Filed: **Aug. 10, 2022**

(30) **Foreign Application Priority Data**

Jun. 13, 2022 (CN) 202230359188.4

(51) **LOC (14) Cl.** **15-09**

(52) **U.S. Cl.**

USPC **D15/144**

(57) **CLAIM**

The ornamental design for a welding machine, as shown and described.

DESCRIPTION

FIG. 1 is a top perspective view of a welding machine showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate the portions of the welding machine that form no part of the claimed design.

1 Claim, 8 Drawing Sheets
